F. A. DILLINGHAM

WINDSHIELD

Filed Aug. 14, 1922

UNITED STATES PATENT OFFICE.

FREDERICK A. DILLINGHAM, OF TROY, OHIO, ASSIGNOR TO THE TROY SUNSHADE COMPANY, OF TROY, OHIO, A CORPORATION OF OHIO.

WINDSHIELD.

Application filed August 14, 1922. Serial No. 581,799.

To all whom it may concern:

Be it known that I, FREDERICK A. DILLINGHAM, a citizen of the United States, and a resident of Troy, in the county of Miami and State of Ohio, have invented certain new and useful Improvements in Windshields, of which the following is a full, clear, and exact description, reference being had to the accompanying drawings, forming part of this specification.

My invention relates to wind shields such as are used in motor vehicles and motor boats, and more particularly to the production of an entirely water-proof shield. The wind shields in the past in which there has been the chance of tilting one section thereof, or more than one section with a view to ventilation, there has always been the difficulty that rain can get through the shield at the ends of the point of juncture between the shields. To avoid water coming in all along the joint between sections, the common practice has been to insert a strip of rubber having a channel to grasp one of the shield sections and adapted to abut against the other.

It is the object of my invention to provide for shield sections which are hinged together all the way across the point of juncture, and in this way to provide a seat for weathering which permits of no leaks whatever along the juncture line. It is also the object of my invention to provide special means in connection with the hinge, whereby weathering is built into it, and which does not have to provide any corner clearance, as in shield sections hung on trunnions.

In connection with trunnion hinged shield sections, a difficulty in the past has been that there has been required a two point clamping for any movable section, one at each trunnion. By my invention I avoid this and can control my movable section or sections from a single point, thereby providing a one-hand operative shield.

Another object of my invention is to provide a shield which is entirely surrounded on the outside by a bearing strip of rubber. This I am enabled to do, and past shields have not embodied, because my form of hinge between the fixed and movable shield sections is such as to flex at a point inwardly of the shield mounting, thereby requiring no clearance to be left, as in a trunnion shield.

Another object of my invention is to provide by my special form of hinge, for a concealment of the edges of the glass at the hinge, thereby avoiding the necessity of grinding and polishing the edges of the glass after it is cut.

The complete rubber flange serving as an abutment for the shield sections on the outside of the shield mounting frame makes it possible to install shields with a neat appearance which do not fit exactly into the opening formed in the mounting frame.

The upholstery, which is universally used in closed cars to face the inside of the shield mounting frame can be brought around and secured on the frame with the rubber flange or other weathering material strip that serves as the shield abutment.

These various advantages and objects I accomplish by that certain construction and arrangement of parts to be hereinafter more specially pointed out and claimed.

In the drawings,

Figure 1 is a front elevation of the shield taken from the inside of the vehicle.

Figure 2 is a section on the line 2—2 of Figure 1.

Figure 3 is a section on the line 3—3 of Figure 1.

Figure 4 is a section on the line 4—4 of Figure 2.

The frame of the shield may be either of wood and part of the car body, or may be of metal and inserted in the car body when the shield is installed.

I have shown a side frame piece 1 having a rabbet or cut away portion 2 in which the shield is to be set with the shoulder 3 of the rabbet located on the outside of the shield. The bottom and top frame pieces 95 may be the same.

Secured entirely around the shield frame on the shoulder 3 is a rubber strip 4 which is curled at the outer edge and mounted by means of metal or wood strips 5, which are screwed to the rabbet shoulder 3. I have not illustrated but it will be understood that upholstery 6 may be brought around the portion 7 of the frame and secured down with the rubber strip. The upholstery is broken away short of this mounting in Fig. 4, for purposes of clearness, and because this is merely a preferred structure and not essential.

I have shown a three section shield, al-

though a two section might preferably be used in cheaper vehicles.

- The central or main section of the shield is made up of side frame pieces 8, which are 5 screwed down against the rabbet shoulder, so as to bring the side frames tip against the rubber strip or flange 4. The glass 9 of this section is equipped with the special hinge to be described, which in the three 10 section shield is located at both top and bottom, and in the two section shield is located at the bottom only, the top edge being screwed down and provided with a frame similar to the side frame pieces.
- 15 The upper and lower shield sections of the form shown have side frame pieces 10 and one cross frame piece 11 for each section. The pieces 11 come at the top and bottom of the shield, it being understood that in the 20 two section form only the bottom section will be provided.

The special hinge device is formed of two long leaves 12 and 13 having knuckles 12^a and 13^a which are held together by a pin 25 tie 14.

In mounting the hinge leaves on the shield sections, the ends of the leaves are screwed to the metal frames of the adjacent sections and the sides as at 15.

30 Vulcanized over the two leaves and if desired not vulcanized over the knuckles, are rubber pieces 16 and 17. These rubber pieces have channels 16^a and 17^a which are thrust over the edges of the glass 9 and 18 35 of the meeting sections and act in this regard similarly to the rubber facing strips now in use for weathering between sections and above referred to.

40 The strips 17 which are mounted on the main section will have preferably curled edges 19 which overlap the sections 17 when the shield sections are closed.

On the movable sections a central control device may be used. As such I have shown 45 for the lower section an arc-shape or curved bar 20 secured to the vehicle and carrying a slider 21, which is connected to the center of the shield section. On the slider is a screw 22 which engages and clamps against 50 the bar 20 holding the shield in adjusted position.

On the upper section the bar 23 which is straight, is used, and the slider 24 controlled by clamp screw 25. The slider is hingedly 55 connected at the center of the upper section, as indicated at 26.

It will be evident from this construction that when closed, the shield has no point 60 which is not fully protected by abutment of rubber against rubber, or rubber against glass or metal. In flexing either movable section to get ventilation, the sections swing inwardly with manipulation by one hand. The small catches 30 shown for each 65 movable section merely swing into slots in

the mounting frame edge. They are not necessary to hold the shield sections firmly, but may be used to get a tighter fit in a heavy storm or a high wind.

The simplicity of mounting, freedom from 70 necessity of polishing any glass edges, one hand manipulation and full water proofness are believed to be obvious without further comment.

The hinge might be of value in other constructions, and I do not wish to limit its use to wind shields alone. When closed, the rubber faces on the hinge plate abut and the curled edge acts as an overlap.

A structure of considerable value could be 80 made with the rubber omitted between the hinge leaves and the overlap only provided as a complete guard. I prefer the structure shown, however.

Having thus described my invention, 85 what I claim as new and desire to secure by Letters Patent, is:—

1. In a wind shield, the combination of a mounting frame, a fixed shield section mounted in said frame, and a movable shield section adapted to fit said frame, and means for hinging the movable section to the fixed section, as distinguished from hinging said movable section to the mounting frame and weathering means incorporated with the 95 hinging means and constituting a seal between the two sections throughout their meeting edges when closed.

2. In a wind shield, the combination of a mounting frame, a fixed shield section mounted in said frame, and a movable shield section adapted to fit said frame, and means for hinging the movable section to the fixed section, as distinguished from hinging said movable section to the mounting frame, and 100 said hinging means comprising plates articulated to each other extending entirely across the juncture of the fixed and movable sections, and weathering means incorporated with the said hinging means constituting a seal between the sections when the fixed section is closed.

3. In a wind shield, the combination of a mounting frame, a fixed shield section mounted in said frame, and a movable shield section adapted to fit said frame, and means for hinging the movable section to the fixed section, as distinguished from hinging said movable section to the mounting frame, and said hinging means comprising plates articulated to each other extending entirely across the juncture of the fixed and movable sections, and rubber strips vulcanized to the said plates, constituting a seal between the sections when the fixed section is closed.

4. In a wind shield, the combination of a mounting frame, a fixed shield section mounted in said frame, and a movable shield section adapted to fit said frame, and means for hinging the movable section to 125

the fixed section, as distinguished from hinging said movable section to the mounting frame, and said hinging means comprising plates articulated to each other extending entirely across the juncture of the fixed and movable sections, and rubber strips vulcanized to the said plates, constituting a seal between the sections when the fixed section is closed, said rubber strips having 10 means for engaging the shield sections as well as the hinge.

5. In a wind shield, the combination of a mounting frame, a fixed shield section mounted in said frame, and a movable shield section adapted to fit said frame, and means for hinging the movable section to the fixed section, as distinguished from hinging said movable section to the mounting frame, said hinging means comprising plates articulated 20 to each other extending entirely across the juncture of the fixed and movable sections, and rubber strips vulcanized to the said plates, constituting a seal between the sections when the fixed section is closed, said 25 rubber strips formed with channels therein, adapted to engage about the edges of the shield sections.

6. A hinge for members, such as wind shield sections, comprising elongated plates,

hinged together, and secured to the parts 30 to be supported, such as wind shield sections, and rubber strips secured to the plates, and having channeled portions to house the hinged edge of one of the supported parts, at least.

7. A hinge for members such as wind shield sections, comprising elongated plates hinged together, and secured to the parts to be supported, such as wind shield sections, and rubber strips secured to the plates, and having channeled portions to house the hinged edge of one of the supported parts 35 at least, said rubber strips being vulcanized over the plates and a portion thereof lying between the plates.

8. A wind shield, in combination with a mounting frame, said frame having a rabbeted portion in which the shield is set, rubber facing extending around the rabbet shoulder forming a complete compressible 50 abutment for the shield, said shield formed of at least two sections, one section being secured fast in the rabbet frame and the other section being hinged to said fixed section, and adapted to swing inwardly of the 55 frame with a rubber facing for the hinged edges of the sections.

FREDERICK A. DILLINGHAM.
